JOSEPH B. MORAN, OF SAN FRANCISCO, CALIFORNIA, ASSIGNOR OF ONE-HALF TO
THOMAS J. MAHONEY, OF SAN FRANCISCO, CALIFORNIA.

WATER-HEATER.

1,165,696.

Specification of Letters Patent.

Patented Dec. 28, 1915.

Application filed March 29, 1915. Serial No. 17,670.

To all whom it may concern:

Be it known that I, JOSEPH B. MORAN, a citizen of the United States, residing in the city and county of San Francisco and State of California, have invented new and useful Improvements in Water-Heaters, of which the following is a specification.

This invention relates to a water heater.

One of the objects of the present invention is to provide a sectional heater which is simple and substantial, and which is so constructed that it can be easily assembled or taken apart to permit interchanging, renewal or cleaning of the different parts.

Another object of the invention is to construct the heater to present as large heating surfaces as possible, and to provide means whereby the water is caused to circulate not only through the different sections of the heater but also through the hot water pipe system with which it is connected.

Further objects will hereinafter appear.

The invention consists of the parts and the construction and combination of parts as hereinafter more fully described and claimed, having reference to the accompanying drawings, in which—

Figure 1 is a central vertical section through the heater. Fig. 2 is a cross section on line 2—2, Fig. 1.

The heater in general is built up of separable sections, such as indicated at 2 and 3. The sections are preferably cast of a suitable metal, such as brass, iron, or the like, and are cored out to form a central chamber 4 and an exterior annular jacket-like water chamber 5. The inner chamber 4 of each section is closed over by a head 6 which is cast or formed integral with the inner wall 7 of the annular water chamber 5, and the upper end of each section is closed by a copper plate 8 which is secured in position by a wrought iron ring 9 and screws 10.

Mounted in each chamber 4 is a bell-shaped, hollow casting 11. This casting is suspended from the head 6 by means of a nipple 12 and communication is thus formed between same and the annular jacket chamber 5. The sections 2 and 3 are separated or elevated, one above the other, by means of a spacing ring 13 to produce a chamber in which is mounted a baffle-shaped heater 14. This chamber is preferably constructed of pressed steel, copper or like material and

is connected at its upper end by means of 55 the slip joint 15 with the upper bell-shaped chamber 11 and at its lower end by a nipple 16 with plate 8. Communication is thus established between the lower annular jacket 5 and the upper annular jacket 5, as 60 the water is permitted to pass through nipple 16, chamber 14, slip joint 15, and the upper bell-shaped chamber 11. It then passes through the upper nipple 12 which communicates directly with the upper an- 65 nular chamber 5.

The heater as a whole, consisting of the sections 2 and 3, is mounted on a suitable stand, such as indicated at 17, and suitably supported in said stand, just below the 70 lower bell-shaped chamber 11, is a gas burner 18. The flame from this burner strikes the bottom of the lower bell-shaped chamber 11 and is then deflected and caused to pass around the exterior of same in an 75 annular passage 19 formed between the inner wall 7 of the annular jacket chamber 5 and the bell-shaped chamber 11. The heat then passes through a series of flues 20 extending through head 6 and plate 8 and 80 will then enter a chamber 13 in which the baffle-shaped heater 14 is mounted. The heat is here deflected, as indicated by arrows a, and will now strike the bottom of the upper bell-shaped chamber 11 and pass 85 exteriorly of same through the annular passage 19a, through flues 20a and will then enter a cover-like section 21 from where the heat is permitted to escape through the 90 vent 22.

The upper cover section 21 is sufficiently large to form a chamber 23 in which is mounted a baffle-shaped heating chamber 14a. This is connected at its lower end with a copper plate 8a which closes the upper end 95 of the upper section 3, and the upper end of the baffle-shaped chamber is connected with an outlet pipe 24, which passes through the cover section 21, and is then connected with the pipes of the hot water system not here 100 shown. The flues 20 and 20a passing through the upper end of each heater section are preferably hexagonal in shape and are provided with short extensions on the lower ends which are screwed into the heads 6 with 105 which they connect. The upper ends are similarly threaded and shouldered to form a seat for the plates 8 and 8a and the plates

are secured on same by means of nuts 25; a suitable packing being interposed to form water-tight connections.

A cold water inlet pipe 26 is preferably connected with the lowermost bell-shaped chamber 11 and is just sufficiently long to extend through the bottom of same, as indicated at 27. The inner end is then capped or closed, as at 28, and a plurality of radially disposed slits 29 are formed in the side of the pipe to direct the incoming water against the bottom of the chamber. This prevents the formation or eliminates any tendency for mud or sediment to collect and cake on the bottom of the chamber.

For the purpose of producing the best circulation possible, as far as water is concerned, a pipe 30 is connected with the upper end of nipple 12. This pipe extends over the edge of the head 6 and is then turned down, as indicated at 31, to force the water down toward the bottom of the annular chamber 5. A vent 32 formed in the bend of the pipe prevents any tendency to form a steam pocket in the pipe 30.

The return pipe from the hot water pipe system, indicated at 33, is preferably connected with a thermostat valve, such as indicated at 34. This valve regulates the flow of gas to burner 18 as it is directly connected with valve 35 on the gas main. The moment the water in the system attains a predetermined degree of temperature or heat it will cause the thermostatic valve to expand and correspondingly open or close the valve 35, thus automatically regulating the burner 18.

Each section 2 and 3 is provided with a clean-out connection 36 to remove any sediment which might have a tendency to collect in the lower portion of the annular jacket-like chamber 5 and one or more doors, such as indicated at 37, may be provided in the spacing ring 13 to permit the cleaning out of the heating flues, etc.

Formed in the cover section 21 is a plurality of openings 21^a and a baffle-plate 21^b. The baffle-plate is provided for the purpose of preventing any down draft through the heater. Any down draft coming through vent 22 will strike the annular baffle-plate 21^b and will immediately pass out through the openings 21^a. The elimination of the down draft protects the several heating surfaces from sudden changes of temperature, thereby preventing contraction and also protecting the pilot light and burner from being extinguished.

The heater, when assembled, is preferably protected by a sheet metal casing, such as indicated at 39, which is lined with asbestos cloth, thus insuring against loss of heat from the hot water which might otherwise be radiated. While the heater is here shown as constructed of two sections, it will be un-

derstood that it may be increased by adding on any suitable number of sections to those already in use. The hot water return pipe connected with the lower section, as indicated at 40, will act as a booster to cause an immediate return of water to the heater from the hot water pipe system, thereby insuring instant hot water at all fixtures connected with the system.

A heater constructed as here shown is simple and substantial in construction and is easily accessible for cleaning and repairing. The large heating surface provided throughout the several sections and chambers formed within the heater permits practically every heat unit to be absorbed by the water, thus greatly increasing the efficiency and capacity of same. The heater can, furthermore, be easily dismantled, as it is only necessary to loosen the coupling and the slip joint 15. Interchanging or renewal of the several parts, when necessary, can thus be easily accomplished.

The materials and finish of the several parts of the heater are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. A water heater comprising, in combination, a casing having a central heating chamber formed therein and an annular jacket-like water chamber exteriorly of the heating chamber, a head closing the upper end of the heating chamber, a plate closing the upper end of the casing, flues extending through the head and plate communicating with the heating chamber, a bell-shaped, hollow casing centrally positioned within the heating chamber, a nipple connecting same with the annular water chamber, a water inlet pipe connected with the bell-shaped casing, and an outlet pipe connected with the head.

2. A water heater comprising, in combination, a casing having a central heating chamber formed therein and an annular jacket-like water chamber exteriorly of the heating chamber, a head closing the upper end of the heating chamber, a plate closing the upper end of the casing, flues extending through the head and plate communicating with the heating chamber, a bell-shaped, hollow casing centrally positioned within the heating chamber, a nipple connecting same with the annular water chamber, a water inlet pipe connected with the bell-shaped casing, said pipe extending into the

chamber formed interiorly of the bell-shaped casing and having a plurality of radially disposed discharge slots formed therein, and an outlet pipe connected with the plate.

5 3. A water heater comprising, in combination, a casing having a central heating chamber formed therein and an annular jacket-like water chamber exteriorly of the heating chamber, a head closing the upper end of the heating chamber, a plate closing the upper end of the casing, flues extending through the head and plate communicating with the heating chamber, a bell-shaped, hollow casing centrally positioned within the heating chamber, a nipple connecting same with the annular water chamber, a cover casing mounted above the plate, a hollow baffle-shaped casing mounted interiorly of 10 said casing, a nipple connecting the lower end of the baffle-shaped casing with the plate to form communication with the annular water chamber, an outlet pipe connected with the upper end of the baffle-shaped 15 casing, and an inlet pipe connected with the bell-shaped casing.

20 4. A water heater comprising, in combination, a casing having a central heating chamber formed therein and an annular jacket-like water chamber exteriorly of the heating chamber, a head closing the upper end of the heating chamber, a plate closing the upper end of the casing, flues extending through the head and plate communicating 25 with the heating chamber, a bell-shaped, hollow casing centrally positioned within the heating chamber, a nipple connecting same with the annular water chamber, a cover casing mounted above the plate, a hollow baffle-shaped casing mounted interiorly of 30 said casing, a nipple connecting 35

the lower end of the baffle-shaped casing with the plate to form communication with the annular water chamber, an outlet pipe connected with the upper end of the baffle- 45 shaped casing, an inlet pipe connected with the bell-shaped casing, a vent pipe connected with the cover casing, and means for preventing a down draft through the cover casing.

50 5. A heater of the character described, comprising, in combination, a plurality of superposed casings, each having a central heating chamber formed therein and an annular jacket-like water chamber exteriorly of the heating chamber, a head closing the upper end of each heating chamber, a plate closing the upper end of each casing, a spacing ring interposed between each casing, a burner mounted in the lower heating chamber, a plurality of flues extending through each plate and head to permit the heat to pass through the several heating chambers, a baffle-shaped, hollow casing mounted above each plate, connections 55 formed between each annular jacket-like water chamber and baffle-shaped casings to permit the water as it heats to circulate in an upward direction through the several connected chambers, an outlet pipe connected with the uppermost baffle-shaped casing, and a water inlet pipe connected with the lowermost annular jacket-like water chamber.

60 In testimony whereof I have hereunto set 75 my hand in the presence of two subscribing witnesses.
